CLAIM

The ornamental design for a canister as shown.

DESCRIPTION

FIG. 1 is a top isometric view of a canister according to a first embodiment;

FIG. 2 is a bottom isometric view of the canister illustrated in FIG. 1;

FIG. 3 is a side view of the canister illustrated in FIG. 1; FIG. 4 is a side view, which is opposite the side view of FIG. 3, of the canister illustrated in FIG. 1;

FIG. 5 is a rear side view of the canister illustrated in FIG. 1;

FIG. 6 is a front side view of the canister illustrated in FIG. 1;

FIG. 7 is a top view of the canister illustrated in FIG. 1; and, FIG. 8 is a bottom view of the canister illustrated in FIG. 1. The broken lines in the drawings form no part of the design to be patented.

1 Claim, 8 Drawing Sheets
